UNITED STATES PATENT OFFICE

CLIFFORD SIDNEY BROWN, OF JERSEY CITY, NEW JERSEY

BOOK AND STORAGE STACK

Application filed November 1, 1928. Serial No. 316,404.

This invention relates to book and record storage stacks for libraries and record storage buildings.

In the general construction of book and record storage stacks it is more or less customary to provide a central column for the support. In some cases the book rack shelves are supported from the column by brackets and in other cases cast iron shelf supports are used. Among the disadvantages of such construction might be mentioned the effect of such cantilever support in increasing the overturning or bending moment of the columns and the difficulties inherent in the use of cast iron in connection with steel to say nothing of the high cost of construction of such stacks.

One of the objects of this invention is to provide a book and record storage stack capable of supporting the ceiling and roof over the stack room and acting as a brace for the main building structure, and to conveniently support a plurality of shelf ranges, one upon the other, with stack floors or decks at each range for gaining easy access to the shelves.

Another object of this invention is to provide a structure wherein the columns support their greatest variable loads directly, to wit, the live load of the books or records, and thereby maintaining the bending moment at the minimum.

A further object of the invention is to provide a simple and economical structure whereby the columns are placed on each side of the range center at the point of maximum load and to provide minimum spans for the deck framing members and also to provide more head room for the tier below. Still another object of the invention is to provide book and record storage stacks wherein the columns may be of readily fabricated steel, which columns are also used to support the book shelves.

Still another object of the invention is the provision of a book or record storage stack in which simple and unique means are employed to support the books and records and provide for the vertical and horizontal adjustment of the shelves without the use of bolts or any other loose connecting members.

A still further object of this invention is to provide a removable, adjustable form of shelf composed of hollow bars having spaces between and secured to end supporting members and forming a unit shelf of reversible sides of strong but light construction.

A still further object of my invention is to provide a stack structure which will accommodate the greatest amount of book or record space in a given space.

Referring to the drawings:

Figure 1 is a diagrammatic plan view of a device embodying the principles of my invention showing ranges and aisles and the use of different sizes of shelves.

Figure 2 is a view in side elevation of a part of two ranges and an aisle between, showing a tier and part of the tier above.

Figure 3 is a perspective view showing a portion of two tiers with the intervening deck or ceiling at a range partition.

Figure 4 is a detail sectional plan view of a range partition along the line 4, 4, of Figure 5, looking in the direction of the arrows.

Figure 5 is a detail sectional elevation of a range partition, along the line 5, 5, of Figure 4, looking in the direction of the arrows.

Figure 6 is a detail sectional plan view of a range end, along the line 6, 6, of Figure 7, looking in the direction of the arrows.

Figure 7 is a detail sectional end elevation of a stack range, along the line 7, 7, of Figure 6, looking in the direction of the arrows.

Figure 8 is a detail view showing a section along the line 8, 8, of Figure 7, looking in the direction of the arrows, of a range end at a deck level.

Figure 9 is a detail sectional plan view showing the adjustable shelf construction, along the line 9, 9, of Figure 5, looking in the direction of the arrows.

Figure 10 is a detail sectional side view of a range end at a deck level, along the line 10, 10, of Figure 7, looking in the direction of the arrows.

Figure 11 is a detail sectional view of the column ties and two adjacent fixed shelves along the line 11, 11, of Figure 5, looking in the direction of the arrows.

In carrying out my invention, I propose to provide a structure of unique simplicity having a minimum number of members of light weight and yet strong. As shown diagrammatically in Figures 1 and 2, the structure is composed of a plurality of ranges A, spaced apart to provide aisles B, to permit of ready access by means of the aisles to either side of a range. The range is composed of a plurality of superimposed tiers, each tier occupying the space which lies between two adjacent stack floors or decks. The vertical dimension of each tier is governed by various conditions such as the number of compartments desired, a compartment being that space bounded vertically by fixed shelf 1 at a deck and fixed shelf 1 at the next adjacent deck and horizontally by two range partitions C, or a range partition C and a range end D. As books or records of various sizes may be stored in the compartments, I provide adjustable means of division in the form of adjustable shelves 2 which latter may be of various widths, as shown, particularly in Figure 1. Shelves 2 are interchangeable, that is, any shelf 2 in any part of one compartment may be changed to any other place in the same compartment or in any other part of another compartment of the same length. Compartment lengths may be varied to suit conditions. The bottom shelf in a compartment being fixed shelf 1. The latter may be used in any compartment of the same length as the bottom shelf but is not removable or adjustable for use in the same compartment. The width of fixed shelf 1 is generally the same as ranges A. The purpose of fixed shelf 1 is to separate the tiers and to act as a fire and dust stop. Fixed shelf 1 may also function as a part of the ventilating system of the stack room. This is accomplished by continuing the stiffening flange 1^a down to the curb angle 3 and thereby provide an air stop. In this way complete tiers may be ventilated separately, which in large stack rooms is quite desirable. The ventilating space E would then be closed off. As previously indicated, fixed shelf 1 is the bottom shelf to support books or records in each compartment. Fixed shelf 1 is of the same length as the compartment and is bolted to the column tie angles 4 and in case it is to be used as an air stop it would also be bolted to the curb angles 3.

Column tie 4 is used to assist in the location and support of columns 5 and to support fixed shelf 1. I have shown column tie 4 as an angle although other shapes might be used. Column tie 4 is preferably made of steel as it is part of the stack structure. Curb angle 3 is also used as a locating and supporting member for columns 5 as well as the support for flooring 6. For the same reasons as column tie 4 is preferably made of steel so too I prefer to make curb angle 3 of steel.

Some protection must be given to the exposed portion of curb angle 3 by reason of the necessity of mopping and cleaning the floors. To protect the exposed portion, I propose to paint it or to cover it with a strip of non-corrosive metallic material. Other means of protection may be used such as the use of non-corrosive metal.

Deck framing members 7 are also essential parts of the structure as they support flooring 6 and columns 5. Members 7 should likewise be of steel. In the structure I have shown the cross sectional area of framing members 7 which will be a comparative minimum as the location of columns 5 produce spans for the deck framing members 7 of minimum length as compared with the usual form of construction wherein the columns are in the center of the stack. It should be noted that the support of the whole structure is taken care of directly by columns 5 as they are located at each side of range A at the range partition C and the range end D. Columns 5 may be in several tier lengths and are preferably made of unit steel shapes and may extend from the basement to the uppermost tier and support the ceiling and roof. The use of column 5 of a unit shape is very economical as it greatly facilitates fabrication, shipping and erection. Although I prefer to use fabricated steel for columns 5, other materials might still be used. Where it becomes necessary to splice columns 5, bent bars (not shown) can be used on the inside and the curb angles 3 and the framing angles 7 can be used on the outside. The stack structure may be assembled by welding, riveting, bolting or other well known means.

Shelf strip 8 is secured to columns 5 in any well known manner such as by bolts and is preferably of pressed steel in which is punched the lugs or teeth 8^a to accommodate slots 2^c in adjustable shelves 2 thereby permitting vertical and horizontal adjustment of shelves 2.

Adjustable shelves 2 are composed of hollow bars 2^a spaced for ventilation of the books and records and locked in their proper locations by end hollow bars 2^b as shown in Figures 4, 5, 6, 7 and 9. Adjustable shelf 2 may be made of any metal. The longitudinal bars 2^a have their surfaces slightly rounded to give a line bearing to the books or records in order to prevent dust collecting on the surface from contacting with the books or records as is the case of flat surfaces. The adjustable shelves 2 are readily adjusted both vertically and horizontally by means of lugs or teeth 8^a in shelf supporting strips 8. As slots 2^c are provided in each side of adjustable shelf 2, either side may be used as the top. The form of assembly of the bars 2^a and bars 2^b is particularly shown in Figure 9. Bars 2^a having two of their sides cut out

to receive bars 2^b and are then bent to encircle bars 2^b.

In order to improve the appearance where the stacks are to be exposed I provide a steel range end 9 which is bolted to columns 5 at range end D at the sides and to curb angles 3 at the top and bottom. Range indicators, electrical contacts, etc., (not shown) may be fastened conveniently to the steel range end. The structure admits of electrical lighting of the stacks throughout, the conduits being supported by deck framing 7 and the controls being placed at the range ends D.

What I claim is:—

1. A book and storage stack comprising a plurality of ranges, aisles between said ranges, said ranges and aisles composed of a plurality of superimposed tiers, stack floors, each tier occupying the space lying between two adjacent stack floors, said ranges divided into compartments by range partitions, vertical columns forming supporting means and positioned on both sides of the ranges and aisles and deck framing members supported by said vertical columns, said deck framing members adapted to support the stack floors.

2. A book and storage stack comprising a plurality of ranges, aisles between said ranges, said ranges and aisles composed of a plurality of superimposed tiers, stack floors, each tier occupying the space lying between two adjacent stack floors, said ranges divided into compartments by range partitions, vertical columns forming supporting means and positioned on both sides of the ranges and aisles, adjustable shelves in each compartment, means for adjustably supporting said shelves between said columns in each compartment and deck framing members connecting said columns and supported thereby, said deck framing members supporting said stack floors.

3. A book and storage stack comprising a series of superimposed tiers of ranges and aisles, each tier separated by stack floors, parallel rows of vertical unit supporting columns, each of said ranges extending between and bounded by two rows of said parallel columns, each of said aisles extending between two rows of parallel columns, deck framing members of minimum length to connect adjacent rows of said columns, said deck framing members adapted to support said stack floors, range partitions in said ranges to divide the space between two parallel rows of columns into range compartments, adjustable shelves in said compartments, means carried by said columns to adjustably support said shelves between said parallel rows of columns.

4. A book and storage stack comprising a plurality of ranges, aisles between said ranges, said ranges composed of a plurality of superimposed tiers, stack floors, each tier occupying the space lying between two

adjacent stack floors, rows of vertical parallel columns of unit steel shapes extending a plurality of tiers, each range extending between two parallel rows of columns, said ranges divided into compartments by range partitions, a fixed shelf at the bottom of each compartment, a column tie member to support said fixed shelf, curb angles to support said stack flooring and connected to said columns, deck framing members connected to said column to support said stack flooring, adjustable shelves in each compartment, means for adjustably supporting said shelves, said adjustable supporting means being secured to and supported by said columns.

5. A book and storage stack comprising a plurality of ranges, aisles between said ranges, said ranges composed of a plurality of superimposed tiers, stack floors, each tier occupying the space lying between two adjacent stack floors, rows of vertical parallel columns of unit steel shapes extending a plurality of tiers, each range extending between two parallel rows of columns, said ranges divided into compartments by range partitions, a fixed shelf at the bottom of each compartment, a column tie member to support said fixed shelf, curb angles to support said stack flooring and connected to said columns, deck framing members connected to said column to support said stack flooring, adjustable shelves in each compartment, means for adjustably supporting said shelves, said adjustable supporting means being secured to and supported by said columns, and means for ventilating each vertical tier of compartments.

6. A book and storage stack comprising a plurality of ranges, aisles between said ranges, each of said ranges divided into compartments by range partitions, vertical columns in parallel rows forming supporting means, said columns positioned on both sides of the ranges, said range compartments of lesser width than the parallel rows of columns bounding the range, adjustable shelves in each compartment, said shelves formed of tubing, means for hanging said shelves on supporting shelf strips, said shelf strips secured to said columns and extending inwardly therefrom.

7. A book and storage stack comprising a plurality of ranges, aisles between said ranges, each of said ranges divided into compartments by range partitions, vertical columns in parallel rows forming supporting means, said columns positioned on both sides of the ranges, said range compartments of lesser width than the parallel rows of columns bounding the range, adjustable shelves in each compartment, said shelves formed of tubing, means for hanging said shelves on supporting shelf strips, said shelf strips secured to said columns and extending inwardly therefrom, said shelf strips having a plu-

rality of supporting means to accommodate shelves of different widths.

8. A book and storage stack comprising a plurality of ranges, aisles between said ranges, range ends at the end of said ranges, range partitions in each of said ranges, fixed shelves at the bottom of each range, compartments formed by said range partitions, fixed shelf and ceiling, parallel rows of vertical columns forming supporting means and bounding said ranges, the distance between said columns being greater than the width of a range, shelf strips secured to the inside of said columns and extending inwardly to the range, a plurality of rows of lugs to support varying widths of shelves, reversible adjustable shelves formed of hollow tubing having end tie members, openings in said tie members to receive said lugs to support said shelves.
